UNITED STATES PATENT OFFICE.

CHARLES L. SAWYER, OF ERVING, MASSACHUSETTS.

WIRE-TIGHTENER.

SPECIFICATION forming part of Letters Patent No. 791,583, dated June 6, 1905.

Application filed November 14, 1904. Serial No. 232,765.

To all whom it may concern:

Be it known that I, CHARLES L. SAWYER, a citizen of the United States, residing at Erving, in the county of Franklin and State of Massachusetts, have invented certain new and useful Improvements in Wire-Tighteners; and I do declare the following to be a full, clear, and exact description of the invention, such as will enable others skilled in the art to which it applies to make and use the same.

My invention relates to wire-tighteners designed more especially for use by electricians in wiring inside work; and one of the objects of the same is to provide a device of comparatively simple construction which will grasp two parallel wires and stretch them properly through the cleats which serve to secure the wires to a wall or ceiling.

Another object is to provide a special tool for this class of service which will be comparatively quick in its action and which will yield to the varying conditions in taking up the slack insulated wires.

I attain these and other objects by means of the construction illustrated in the accompanying drawings, in which—

Figure 1 is a perspective view of a device made in accordance with my invention and showing the tightener in position for stretching the wires and also showing in dotted lines the position which the structure is made to assume to draw the wires tightly through the cleat. Fig. 2 is a longitudinal section through the gripping-jaw. Fig. 3 is a transverse section of the same. Fig. 4 is a detail view of one of the jaws. Fig. 5 is a similar view of the other jaw, and Fig. 6 is an under side plan view of a jaw guide or keeper.

Referring to the accompanying drawings for a more particular description of my invention, the numeral 1 designates a frame or base portion provided with a foot 2, which extends upwardly to form a bridge, the opposite side of said bridge being provided with an abutment 3, designed to bear against one edge of a cleat, as shown in Fig. 1, and at points near the outer ends of the abutment grooves or slots 4 are formed in extensions 5 of said abutment, said grooves or slots being substantially the same distance apart as

the parallel wires used for inside work on electric wires for fans and other similar devices. An arm 6 extends centrally from the abutment, and its outer end 7 is curved upwardly, as shown, to provide a bearing for a 55 pintle 8, which passes through the bearings 9 in a stretching-lever 10 to pivot said lever to the arm 6. At the outer end of the stretching-lever 10 a pair of gripper-jaws are mounted to move laterally within a guideway or keeper 11, said guideway being provided with an elongated slot 12 and side flanges 13, which are grooved on their inner walls, as at 14. The movable jaws 15 16 are connected to the guideway 11 by means of lugs 17, bent to 60 embrace the edges of the keeper. Stops 18 are formed by the projecting ends 19 of the flanges 13, as shown. The movable jaw 15 is provided with a tapering cam or rib upon its inner edge, while the jaw 16 is provided with 65 a similar cam or rib to overlie the cam on the jaw 15, as shown, each jaw having a groove 20 upon its outer edge and a pin or screw 21 passing through the outer end of the lever 10 and through the elongated slot 12 and extending between the cams upon the inner 70 edges of the jaws, said jaws sliding on the pin 21 and said pin bearing against the cams to open or close the jaws, according to the direction of strain. A washer 23 bears upon 75 the surfaces of the cams to insure a smooth sliding operation of the pin.

The operation of my wire-stretcher may be described as follows: The frame is placed with the abutment against one edge of a cleat, 80 and the wires are passed over the abutment and through the slots or grooves in the extended ends thereof, the stretching-lever then occupying the position shown in full lines in Fig. 1. The wires are passed upward between 85 the outer edges of the jaws and the flanges on the guideway or keeper. The stretching-lever is thrown down to the position shown in dotted lines, the result of which operation is to clamp the wires tightly within the jaws by 90 the action of the pin and cam as the wires are stretched, owing to the increased distance between the abutment and the jaws after the lever has been thrown to the dotted-line position. While in this position the screws *a* in 95 100

the cleat may be tightened and the stretching device subsequently removed.

From the foregoing it will be obvious that my wire-stretcher when placed in position even when used in wiring a ceiling will be held or supported in place, because the lever 10 is forced past the line of dead-center, and it thus becomes easier for it to remain in the air than to fall past the point of greatest tension. It thus leaves both hands of the operator free.

My device may be manufactured at comparatively slight cost and will be found a very efficient and desirable tool for use by electricians.

Having thus described my invention, what I claim, and desire to secure by Letters Patent, is—

1. In a device of the character described, a frame provided with an abutment having extensions, a lever pivoted to said frame and carrying a pair of sliding jaws, cams on the jaws, and a pin on the lever intermediate the cams, substantially as described.

2. In a wire-stretcher, a frame provided

with an abutment having grooved lateral extensions, an arm extended from said abutment, a lever pivoted to said arm, a guideway connected to said lever, a pair of sliding jaws within the guideway, cams on the jaws, and a pin intermediate the cams, said jaws sliding on said pin to clamp parallel wires between the outer edges of the jaws and the guideway, substantially as described.

3. A wire-stretcher comprising a frame or bridge, an abutment, an extended arm, a stretching-lever pivoted to said arm, a guideway provided with a slot and connected to said lever, a pair of jaws provided with cams, a pin intermediate the cams and lugs on the jaws for connecting them to the guideway, substantially as described.

In testimony whereof I have hereunto set my hand in presence of two subscribing witnesses.

CHARLES L. SAWYER.
